UNITED STATES PATENT OFFICE.

GEORGE GENTLE, OF LONDON, COUNTY OF MIDDLESEX, ENGLAND.

BEDSTEAD.

SPECIFICATION forming part of Letters Patent No. 275,187, dated April 3, 1883.

Application filed January 31, 1883. (No model.) Patented in England December 23, 1882, No. 6,154.

To all whom it may concern:

Be it known that I, GEORGE GENTLE, a subject of the Queen of Great Britain, residing at London, in the county of Middlesex, England, 5 have invented new and useful Improvements in Bedsteads, of which the following is a specification.

Bedsteads constructed according to this invention, although having to some extent the outward appearance of an ordinary double bedstead, constitute in reality two distinct beds, (or it might be three or more beds, if desired.) In a sanitary point of view, as compared with an ordinary double bedstead, the new combination-bedstead is most advantageous, also as regards economy of space and of cost, because the new bedstead in many cases will take the place of two single bedsteads. These bedsteads are applicable in private houses where 15 double bedsteads are now used, and in hotels, barracks, hospitals, schools, and children's bed-rooms.

Figure 1 shows a perspective view of the new combination-bedstead, my invention being shown applied to the now most commonly used and approved form of iron bedstead; but my invention is equally applicable to any construction or form of metallic or wooden bedstead. The frame on which the mattress or 20 bed usually rests is divided in two parts or frames. These consist, first, of the two outside ordinary side pieces or bars, A A', the two ordinary end pieces or bars, E and F, the four ordinary standards or posts, G and H, connected thereto in any known or approved manner, and forming part of the ordinary bottom and 25 top or foot and head pieces or frames, I and J, respectively; and, secondly, of the longitudinal bars B and B', which are connected to the end bars, E and F, in any suitable or well-known manner. The laths C and D are connected to the longitudinal bars A B and A' B' and to the cross-bars E and F in the ordinary or other suitable manner, and so as to 30 form, so to say, two distinct beds on one frame or in one piece of furniture. K K and K' K' are legs for giving a firm support to the mid-

dle part of the bedstead. The space provided between the bars B and B', and which may be from ten to twenty centimeters in width, affords facility for the quilt, blankets, or other covering to enter, and serves especially to give the separateness of beds, which, on sanitary and other grounds, is of so great importance. 50

Fig. 2 shows a combination-bedstead ready for use with bed-clothes and hangings or drapery suitable for domestic use.

In Fig. 3, I have shown a modification of an end bar, E or F, which in this case is made in two outer parts, E and E', with a middle connecting-piece, E².

Fig. 3^a shows the connecting-piece E² removed.

Fig. 4 is a part view of the two bars B B', having one leg K in common, instead of one leg for each, as in Fig. 1.

Fig. 5 is a part view of the middle part of the bedstead, showing the central legs, K K and K' K', applied to the longitudinal bars B B' some distance from the end of same. 70

Fig. 6 is an outline view or diagram of a combination-bedstead in which the two frames are connected by the head-frame and the foot-frame, and by the middle connecting-piece, E², applied in the manner shown at Figs. 3 and 3^a, either at head or foot or both. 75

I claim—

1. A combination-bedstead consisting of a double under frame or two under frames, which is or are united at the head and at the foot by 80 a common head-frame and a common foot-frame, substantially as and for the purposes set forth.

2. The double under frame or frames, A B B' A' E F, in combination with posts and legs 85 G H, and head-frames J, and foot-frame I, substantially as and for the purposes set forth.

3. The under frame, A A' E F, in combination with the longitudinal bar or bars B B', substantially as and for the purposes set forth. 90

GEORGE GENTLE.
